GOLF APPARATUS

Robert E. Adams, New York, N. Y.

Application February 16, 1932. Serial No. 593,345

8 Claims. (Cl. 273—32)

This invention relates to apparatus for use in playing the game of golf, and more particularly in playing a modified game on more or less restricted areas.

5 Instead of employing miniature golf apparatus as has frequently been proposed, it is often desirable to employ full size balls and clubs and to drive freely from the tee, as in a standard game, even though the area available is so small as to make an ordinary drive impossible.

The object of the present invention is, therefore, to provide apparatus for so controlling the flight of a golf ball after it leaves the tee as to make it possible to drive freely on restricted areas such as lawns or backyards, and to play a game of golf closely approximating the standard game.

In certain of its aspects, the present invention may be considered as a further development of or improvement upon the apparatus disclosed in my prior copending application, Serial No. 520,416, filed March 5, 1931.

In order that the invention may be readily understood, reference is had to the accompanying drawings, forming part of this specification, and in which:

Fig. 1 is a front view of my improved flight controlling apparatus as it appears when set up on a lawn or the like;

30 Fig. 2 is a transverse section on the line 2—2 of Fig. 1;

Fig. 3 is a plan view of the apparatus shown in Figs. 1 and 2;

35 Fig. 4 is a fragmentary enlarged detailed section taken substantially on the line 4—4 of Fig. 2, looking in the direction of the arrows;

Fig. 5 is an enlarged transverse section through one of the frame members hereinafter described;

40 Fig. 6 is a fragmentary enlarged detail taken substantially on the line 6—6 of Fig. 2, looking in the direction of the arrows; and

Fig. 7 is a perspective view illustrating the appearance of my improved apparatus in connection with the fairway.

45 The means which I employ in the present invention to control the flight of the balls is somewhat similar in principle to that disclosed in the above identified application, that is to say, it comprises a vertical frame 1, from which is suspended a curtain 2. As clearly shown in Fig. 1, the lower edge 3 of this curtain is of curved or irregular outline or profile, instead of being straight, the particular profile illustrated comprising an upwardly curved arch at the center and depending portions at each side.

Secured to the main frame 1 is an auxiliary U-shaped frame 4, adjustable about pivot joints 4^a, and extending upwardly and rearwardly from the mid-portion of the main frame. The frame 4 normally lies in a plane forming an acute angle

with the main frame, and by means of the pivot joints and clamping nuts 4^b, this angle may be varied as required.

Secured to this auxiliary frame 4 is a second or lower curtain 5, this curtain being bent at 5^a and continuing down to provide a freely hanging lower portion 5^b. The upper edge of the curtain 5 is preferably secured to a flat U-shaped bar mounted upon the frame 4, the purpose of this being to avoid the formation of a hump or bump at this point and to maintain the upper surface of the curtain 5 in a true plane.

In order to avoid the formation of a rigid or non-yielding structure at the bend of the curtain 5, it is desirable not to employ any transverse supporting rod or bar at this point. The curtain is therefore supported adjacent the bend solely at its edges, the particular supporting means illustrated in the drawings comprising suitable lacing 7 looped around the frame 4 and passing through grommets 8 in the side edges of the curtain, as clearly shown in Fig. 6. This lacing 7 also provides a convenient means for stretching or tensioning the curtain at this point, so that there is presented to the balls at the bend of the curtain a taut resilient convex surface.

Disposed above the inclined portion of the curtain 5 is a baffle or deflector supported on a third frame 9 secured to the frame 4. This deflector, which is preferably flat, as shown in Fig.

2, may well consist of a piece of canvas 10, looped around supporting members 11 at each end and stretched between the side portions of the frame 9.

Although this baffle or deflector will normally lie in a substantially horizontal plane, as shown in Fig. 2, it is desirable to be able to adjust it angularly, as desired. This may be accomplished by pivotally supporting the end members 11 on bolts 12 and by providing associated clutch members 13, carried by the members 11 and the frame 9, respectively.

By loosening the nuts on the bolts 12, it is obvious that these clutch members may be disengaged and the supporting members 11 swung about the pivot bolts 12 to any desired angular position. By again tightening the nuts, the clutch members will hold or lock the supporting members 11 in adjusted position.

By reference to Fig. 2, it will be seen that the axis about which the baffle or deflector 10 may thus be angularly adjusted is a horizontal axis which is substantially parallel with the bend 5^a in the curtain 5.

In front of the flight controlling apparatus, above described, I propose to locate a low fence or barrier 14, between the apparatus and the tee, so as to prevent the ball from being driven from the tee beneath the curtain 5. Also below the curtains 2 and 5 and between the side members of the frame 1, I provide an inclined surface 15 sloping rearwardly in a direction away from

the tee. These elements 14 and 15 are similar to and serve the same purpose as corresponding elements shown and described in my above mentioned prior application.

- 5 Also as in said prior application, I propose to depict on the front of the curtains 2 and 5, suitable scenery and representations of a green and various bunkers or other hazards to add to the attractive appearance of the apparatus. Also, in 80
10 some cases, and where feasible, I propose to so arrange the layout of the grounds that there is provided behind the said curtains and deflectors a fairway having a green and bunkers or other hazards corresponding in position with those depicted upon the curtain.

15 In Fig. 7, I have attempted to illustrate this. In this figure, 16 designates the tee, and the other parts are indicated by the reference characters already described in the previous figures. The 20 fairway is indicated at *x*, and A designates a green, B bunkers, and C, trees or shrubbery. By reference to Fig. 1, it will be seen that I may depict on the lower portion 5^b of the curtain 5 and also on the curtain 2, a green *a*, bunkers *b*, and 25 trees or shrubbery *c*, all in the same relative location as they appear on the actual grounds behind the curtains. In Fig. 7, D designates a sand trap or the like.

30 In operation, it will be seen that a ball driven from the tee 16 may, by a skilful shot, be caused to pass under the arched portion 3 of the curtain 2, so that it will strike against the inclined curtain 5. From thence, it will be deflected upwardly and impinge against the baffle 10, and by 35 this baffle, be deflected downwardly again to the fairway, all as indicated by dotted lines in Fig. 7. It will also be obvious that a shot driven at a slightly different elevation will strike the curtains 5 and 10 at slightly different angles and will thus 40 be deflected downwardly at a different point, perhaps into the sand trap D, or perhaps nearer to the green A. Should the shot strike the curtain 2, or should it strike the portion 5^b of the curtain 5 at a point below the bend 5^a thereof, it 45 will drop down upon the inclined surface 15 and roll underneath the curtain 5^b rearwardly and out upon the fairway.

50 From an inspection of Fig. 1, it will be understood that the two curtains 2 and 5^b constitute a substantially vertical barrier having an opening therethrough formed by the arched edge 3 of the curtain 2, and that it is the object of the player to drive the ball through this opening. After passing through this opening, the ball is 55 deflected first upwardly and then downwardly onto the fairway.

60 In order to prevent a violent rebound of the ball, I preferably cover the side members of the frame 1 with soft packing, as shown at 1^a in Fig. 5 and I may, in practice, paint or otherwise ornament these padded frame members so as to cause them to conform with the rest of the scenery depicted upon the curtains.

65 As shown in Fig. 7, I also preferably mount an inclined stop or net 1^b above the curtain 2, so as to prevent excessively high shots from going out of bounds.

70 It will be understood that the freely hanging curtains 2 and 5 will yield to such an extent as to prevent any appreciable rebound of the balls therefrom, such balls merely being arrested by the curtains and dropping down upon the surface

15. It will also be understood that the upper portion of the curtain 5 may be put under tension by lacing or other suitable means in order to provide a smooth and resilient surface from which the balls may be deflected. While I have shown the deflectors 5 and 10 as formed of curtains or fabric, it is obvious that other materials may be employed without departing from the spirit of the invention.

85 What I claim is:

1. Means for controlling the flight of a golf ball comprising a substantially vertical yieldable barrier having an opening therein, and angularly adjustable means behind said barrier for deflecting a ball passing through said opening.

90 2. Means for controlling the flight of a golf ball comprising a substantially vertical yieldable barrier having an opening therein, and an angularly adjustable baffle behind said barrier for deflecting downwardly a ball passing through said opening.

95 3. Means for controlling the flight of a golf ball comprising a substantially vertical yieldable barrier having an opening therein, a rearwardly and upwardly inclined surface behind said opening, and an angularly adjustable deflector above said surface.

100 4. Means for controlling the flight of a golf ball comprising a substantially vertical barrier consisting of upper and lower free hanging curtains, the bottom edge of the upper curtain having an irregular contour, and the upper portion of the lower curtain being inclined rearwardly behind said irregular bottom edge, whereby balls passing under said edge strike against said inclined portion and are deflected.

105 5. Means for controlling the flight of a golf ball comprising a substantially vertical barrier consisting of upper and lower free hanging curtains, the bottom edge of the upper curtain having an irregular contour, and said lower curtain being bent rearwardly about a horizontal line adjacent the said irregular edge and at the rear thereof to constitute an angularly disposed deflecting surface against which the balls passing under said irregular edge impinge.

110 6. A deflecting device for golf balls comprising a supporting frame, a curtain carried by said frame and having a freely hanging lower portion, the upper portion of said curtain being bent over and inclined rearwardly, the curtain adjacent the bend being supported from said frame wholly by its side edges, and means for putting such portion of the curtain under tension, whereby a convex resilient surface is presented to the balls.

115 7. Means for controlling the flight of a golf ball comprising a curtain having a vertical, freely hanging lower portion and an upwardly and rearwardly inclined upper portion, and a substantially horizontal flat deflector disposed above said inclined portion.

120 8. Means for controlling the flight of a golf ball comprising a curtain having a vertical, freely hanging lower portion, the upper portion of said curtain being bent over and inclined rearwardly, and a flat deflector disposed above said inclined portion, said deflector being angularly adjustable about a horizontal axis substantially parallel with the bend in said curtain.

125 ROBERT E. ADAMS.
